DESIGN FOR A CLOCK-CASE

William K. Sessions, Forestville, Conn., assignor to The Sessions Clock Company, Forestville,
Conn., a corporation of Connecticut

Application February 1, 1937, Serial No. 67,373

Term of patent 7 years

To all whom it may concern:

Be it known that I, William K. Sessions, a citizen of the United States, residing at Forestville, in the county of Hartford and State of Connecticut, have invented a new, original, and ornamental Design for a Clock-Case, of which the following is a specification, reference being had to the accompanying drawing, forming part thereof.

Fig. 1 is a perspective view of a clock-case showing my new design;

Fig. 2 is a front elevation thereof; and
Fig. 3 is an end elevation thereof.

The design is characterized by the case being of general rectangular form and having a central wide banding and narrow bandings spaced from and on each of the opposite sides of, the central wide banding, said wide and narrow bandings being interrupted by the bezel, and the central wide banding having a width equal to several times the width of either of said narrow bandings.

I claim:

The ornamental design for a clock-case substantially as shown and described.

WILLIAM K. SESSIONS.
